DEVICE FOR ASSISTING IN A HAND-LABELING OPERATION

Eugene H. Pierce, Chicago, Ill., assignor to Swift & Company, Chicago, Ill., a corporation of Illinois

Application October 24, 1945, Serial No. 624,157

4 Claims. (Cl. 216—50)

1

The present invention relates to a container labeling device and more particularly to such a device which may be used to assist in affixing a gummed label to a container.

It is an object of the present invention to provide a container labeling device which is of extremely simple and durable construction and which may be used to associate a label with a container whereby the label may be affixed to the container by hand.

Another object of the present invention is to provide a labeling device which is operable without modification for the application of labels to truly cylindrical containers, or to those which are of tapered configuration.

Still another object of the present invention is to provide a container labeling device which positively lines the container up with a label whereby, with a simple hand operation, the label may be quickly applied to a container.

Yet another object of the present invention is to provide a labeling device for containers in connection with which an adhesive is freshly applied to the end of a label just as the label is to be applied to the container.

Other objects of the invention will be apparent from the following detailed description taken in conjunction with the drawings, in which:

Fig. 1 is a perspective view showing the device as a whole and the method by which it is employed by an operator;

Fig. 2 is a plan view of the device with the cover of the gluepot removed;

Fig. 3 is a vertical sectional view of the device on the line 3—3 of Fig. 2;

Fig. 4 is an enlarged fragmentary sectional view on the line 4—4 of Fig. 2; and

Fig. 5 is a view showing the manner of completing the application of a label to a container.

In the drawings, the numeral 1 designates the base of the device. To the base 1 in opposed relationship are rigidly secured standards 2 which arise therefrom in a substantially vertical plane. These standards may conveniently be rigidly secured to the lateral edges of the base portion 1 as at 4 and 5, but it is to be understood that the exact positioning and the method of securing the standards form no part of the present invention. The standards 2 are provided with oppositely disposed guiding channels 6 for a reason to be brought out fully hereinafter.

The standards 2 together with the channels 6 therein are adapted to receive and position a gluepot, indicated generally by the numeral 8, which is formed of any suitable material but prefe-

reably of metal. The gluepot may conveniently be generally rectangular in shape and its bottom portion may comprise a sheet metal strip 9 having a longitudinally extending slot 10 formed therein. One of the relatively longer and the two shorter side walls of the gluepot 8 may be formed by securing to the bottom portion 9 by soldering or other suitable means a single channel-shaped sheet of metal 11, having its leg portions bent at right angles so as to form laterally extending flanges 12.

The gluepot is completed by securing, as by soldering, the fourth side wall 13 to the bottom portion 9 and flanges 12. The side wall 13 is of sufficient length to produce laterally extending wing portions 14 which serve to position and guide the gluepot 8 in the channels 6 of the standards 2.

Covering the gluepot is a cover member 15 which for convenience has positioned thereon a knob 16. In order to provide for correct positioning of the cover member 15 on the gluepot, the four lateral edges thereof may be recessed as shown at 17 and 18 in Figure 3, and at 19 in Figure 4, so as to leave a thickened portion which will be slightly smaller in dimension than the opening in the gluepot 8.

The lateral dimension of the cover member 15 is made somewhat greater than that of the gluepot 8 so that there are provided wing portions 20 which extend so that their outer extremities are adjacent the standards 2. As shown clearly in Figure 4, the extensions 20 are designed to cooperate with coil springs 22, rigidly and oppositely secured to the base 1 at points adjacent the two shorter sides of the gluepot 8 and arising from the base 1 in parallel relationship with these sides, so as to urge the gluepot 8 toward the base 1 with any desired degree of force. It is readily seen that this may be accomplished by inserting the wing portions 20 between adjacent coils of the springs 22 at any desired distance from the lower ends thereof, thereby adjusting the tension.

A repository for labels, generally indicated by 24, maintaining them in position relative to the gluepot 8, may be conveniently formed by laterally extending side walls 25 rigidly secured in any suitable manner to the base 1 and arising perpendicular thereto. The label repository 24 is closed by a rear wall 26 secured along its lower edge to the base 1 and along its opposed lateral edges to the sides 25. To insure correct positioning of the labels in the repository 24, a filler block 27 presenting a slightly curved surface toward the labels 55 may be secured therein.

A cradle adapted to position the container to which a label is to be applied may be conveniently formed by providing recesses 28 of suitable dimension in the side walls 25 adjacent the gluepot 8. To further aid in the positioning of a container, an abutment 29 may be secured to one of the side members 25 so that at least a portion thereof will extend outwardly with respect to one of the recesses 28 so as to provide a member against which one end of the container may bear.

An abutment 30 is adjustably secured to the base member 1 in front of the gluepot by means of screws 31 and longitudinally extending openings 32. This abutment serves the dual function of regulating the length of a film of glue or other liquid adhesive which is applied to an individual wrapper and automatically aligning the forward edge of a stack of labels which is placed in the label repository at 24 as the stack tends to move forward down the generally inclined plane presented by the filler block 27 through the force of gravity and thus bear against the edge of the abutment 30 presented toward the stack.

From the foregoing description the operation of the device will be obvious. A stack of labels is placed in the repository 24 with the forward edges of the labels abutting the stop member 30 and being supported throughout their length by the filler block 27. The gluepot 8 is then placed in position by insertion of the wing portions 14 in the guide channels 6 and allowed to drop until the bottom portion contacts the top of the first label of the stack. The gluepot is then filled to the desired level with liquid adhesive and the cover 15 placed thereon.

The correct amount of force urging the gluepot downward upon the labels, so as to produce the desired thickness of adhesive film thereon, is provided for by insertion of the extensions 20 between coils of the springs 22 at the necessary height from the lower end thereof.

A container to be labeled is then placed in the cradle of the device with one hand while the other hand picks up the end of the topmost label and places it over the container. The container is given a turn which withdraws the end of the label under the gluepot. This end is then pressed into place upon the end of the label which was previously placed over the container completing the operation.

Although the above description has been directed particularly to a labeling operation in which the individual labels are of such a length that they completely surround the container so that the edges will overlap, it is to be understood that the present device may also be advantageously employed in a labeling operation in which shorter labels are employed. In so employing the device, labels would be used having a film of dried adhesive of the remoistening type on the inner side of each label adjacent the edge thereof which is to be grasped and placed over the container being labeled. It is to be understood of course that this film of dried adhesive would have to be moistened before adhering it to the surface of the container. After this operation has been carried out, however, the container is, as before, given a turn which withdraws the end of the label under the gluepot and this end is then also applied to the surface of the container so that it is adhered thereto, completing the labeling operation.

Because of the inexpensive manufacture of the device which may be composed of any suitable

material, it is feasible to construct different machines for containers of various sizes, but it is to be understood that if desired the device may be made adjustable so that various size containers may be labeled in the same device.

Obviously, many modifications and variations of the invention hereinbefore set forth may be made without departing from the spirit and scope thereof, and therefore, only such limitations should be imposed as are indicated in the appended claims.

What is claimed is:

1. A container labeling device, comprising: a base member; a repository for a stack of labels carried by said base member including side walls and a rear wall rigidly secured to said base member, said side walls having opposed recessed portions therein intermediate the ends thereof adapted to position a container above said stack of labels so that one of the ends of the uppermost of said labels may be readily grasped and wrapped around said container; a gluepot having a longitudinal opening in the lower end thereof; and means guiding said gluepot for vertical movement relative to said base so that said opening in said gluepot contacts the other end of the uppermost of said labels transversely thereof and adjacent thereto.

2. A container labeling device, comprising: a base member; a repository for a stack of labels carried by said base member including side walls secured to said base member, said side walls having opposed recessed portions therein intermediate the ends thereof adapted to position a container above said stack of labels, and means associated with said base to turn one end of the stack upwardly to a position approximately as high as a horizontal plane tangent to the top of a container positioned in said recessed portions so that one of the ends of the uppermost of said labels may be readily grasped and wrapped around said container; a gluepot having a longitudinal opening at the lower end thereof; and means guiding said gluepot for substantially vertical movement relative to said base so that said opening in said gluepot contacts the other end of the uppermost of said labels substantially transversely thereof.

3. A container labeling device comprising: a base member; a repository for a stack of labels carried by said base member including side walls secured to said base member, said side walls having opposed recessed portions therein intermediate the ends thereof and adapted to position a container above said stack of labels, and means to hold said stack of labels curled partially around a container positioned in said recessed portions so that one of the ends of the uppermost of said labels may be readily grasped and wrapped around said container; a gluepot having a longitudinal opening in the lower end thereof; and means guiding said gluepot for substantially vertical movement relative to said base so that said opening in said gluepot contacts the other end of the uppermost of said labels substantially transversely thereof.

4. A container labeling device, comprising: a base member; a repository for a stack of labels carried by said base member including side walls secured to said base member, said side walls having opposed recessed portions therein intermediate the ends thereof adapted to position a container above said stack of labels so that one of the ends of the uppermost of said labels may be readily grasped and wrapped around said con-

tainer; a gluepot having a longitudinal opening in the lower end thereof; and means guiding said gluepot for vertical movement relative to said base so that opening in said gluepot contacts the other end of the uppermost of said labels transversely thereof.
